ELECTRIC KNIFE HANDLE

Samuel Ayres, Jr., Marblehead, Mass., assignor to Signal Manufacturing Company, Salem, Mass., a corporation of Massachusetts

Filed Mar. 16, 1965, Ser. No. 84,280

Term of patent 14 years

(Cl. D22—3)

FIGURE 1 is a top plan view of an electric knife handle embodying my new design;

FIGURE 2 is a side elevational view thereof;

FIGURE 3 is a bottom plan view thereof;

FIGURE 4 is an end elevational view as seen from the right of FIGURE 3; and,

FIGURE 5 is an end elevational view as seen from the left of FIGURE 3.

The cross hatched shading seen in FIGURES 2, 3, 4, and 5 indicates contrasting color with the upper portion of the handle.

The fragmentary broken line showing of the knife blade in FIGURES 1 and 2 is for illustrative purposes only.

I claim:

The ornamental design for an electric knife handle, as shown and described.
